UNITED STATES PATENT OFFICE

THORVALD F. HAMMER, OF BRANFORD, CONNECTICUT

DESIGN FOR A SADDLE RACK

Application filed August 12, 1931. Serial No. 40,837. Term of patent 7 years.

To all whom it may concern:

Be it known that I, THORVALD F. HAMMER, a citizen of the United States, residing at Branford, in the county of New Haven and State of Connecticut, have invented a new, original, and ornamental Design for a Saddle Rack, of which the following is a specification, reference being had to the accompanying drawings, forming part thereof.

Figure 1 is a top or plan view—
Figure 2 is a front end view, and
Figure 3 a rear end view.

I claim:

The ornamental design for a saddle rack, as shown.

THORVALD F. HAMMER.
